(57) CLAIM

The ornamental design a massage bottle, as shown and described.

DESCRIPTION

FIG. 1 is a perspective view of the massage bottle according to the present disclosure;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings are included for the purpose of illustrating the portions of the massage bottle that form no part of the claimed design.

1 Claim, 7 Drawing Sheets
